Geo. N. Goddard, Attorney.

UNITED STATES PATENT OFFICE.

WINDSOR COBB, OF SAN FRANCISCO, CALIFORNIA, ASSIGNOR TO R. BLACKINTON & CO., OF NORTH ATTLEBORO, MASSACHUSETTS, A COPARTNERSHIP COMPOSED OF ROSWELL BLACKINTON, WALTER B. BALLOU, HOWARD M. BALLOU, MYRA A. FREEMAN, AND HELEN G. CUTTER.

COMBINED CIGARETTE HOLDER AND EXTINGUISHER.

1,385,964.

Specification of Letters Patent. Patented July 26, 1921.

Application filed June 28, 1919. Serial No. 307,424.

To all whom it may concern:

- Be it known that I, WINDSOR COBB, a citizen of the United States, and resident of San Francisco, in the county of San Francisco and State of California, have invented certain new and useful Improvements in Combined Cigarette Holders and Extinguishers, of which the following is a specification.
- 10 This invention relates to a smoker's article intended primarily for use as an extinguisher of lighted cigarettes or cigars while adapted at the same time to serve as a holder and also as an ash-tray if desired.
- 15 It is the object of the invention to provide a simple and convenient device which shall insure the quick and convenient extinguishment of a lighted cigar or cigarette to prevent further emission of smoke or 20 fumes which result when the lighted stub is laid on an ordinary ash-tray.

To this end the invention comprises a device comprising a base or support of any convenient form having an upwardly projecting body portion or boss formed with a preferably flared socket open at its upper end into which the lighted end of the cigarette may be thrust, the diameter of the socket approximating to the diameter of a 25 cigarette in order to pinch the lighted end, exclude air and prevent the emission of smoke.

A further feature consists in forming the boss or socket containing member with recesses or notches for supporting a lighted cigarette temporarily. The base may be conveniently formed to serve as an ash-tray.

In the accompanying drawings I have 40 illustrated the preferred form embodying the principles of this invention, in which—

Figure 1 is a plan view;

Fig. 2 is a central cross section;

Fig. 3 is a side elevation partly in cross section showing in dotted lines a cigarette stub inserted for extinguishment;

Fig. 4 is a side elevation showing the device in use as a temporary cigarette holder for a lighted cigarette.

In the practice of the invention according to the form illustrated in the drawings the device consists primarily of a base por-

tion *a* adapted to rest on a table or other flat surface from which base portion projects upwardly a vertical boss *b* provided with an interior vertical socket *c*.

Said socket is open at its upper end and closed at its lower end and is preferably flared toward its upper end both for the purpose of securing a pinching action upon the lighted end of the cigarette and also for accommodating the device to cigarettes or cigars of different diameter. With this end in view the bottom of the socket will be sufficiently narrow in diameter to pinch the smaller sizes of cigarettes so as to exclude air and prevent the escape of smoke.

The raised boss *b* is provided with scallops or notches around its top edge or rim one or more pair of notches being diametrically opposed to form a rack or rest for temporarily supporting a lighted cigarette.

The base *a* may be of any suitable form but in the drawings it is shown provided with a short annular flange or rim *a'* adapted to serve the purpose of an ash-tray.

The device may be formed in any desired or convenient manner but as actually shown in the drawings it is struck up from sheet metal so as to form a hollow annular boss *b* with the socket member drawn downward from the center by suitable forming dies, but, of course, it would be equally possible to cast the same entire.

What I claim is:

1. A cigarette holder and extinguisher comprising a supporting base portion, an upwardly projecting boss formed with an internal vertical socket open at its top and flared from the bottom to the top, the diameter of said socket at some intermediate point being approximately equal to the diameter of a cigarette whereby a cigarette when inserted with its lighted end downward is pinched to exclude air and prevent the escape of smoke fumes therefrom, substantially as described.

2. A cigarette holder and extinguisher comprising a supporting bottom or base portion and a vertically projecting boss formed with an interior socket open at its upper end and closed at its bottom, said socket being approximately of the diameter of a cigarette or the like to pinch the in-

serted lighted end thereof to exclude air and prevent escape of smoke fumes, substantially as described.

3. A smoker's article of the class described comprising a tray-like bottom portion, a boss vertically projecting therefrom and provided with an interior socket closed at its lower end and open at its top, said socket corresponding in diameter approximately to the diameter of a cigarette or the like at some intermediate portion, substantially as described.

4. A smoker's article of the class described embracing in its construction a tray-like base whose middle portion is formed with an upwardly projecting boss provided with an interior flared socket open at its upper end and closed at its bottom, the upper edge of said boss between the socket and its periphery being scalloped as and for the purpose described.

In witness whereof, I have hereunto set my hand, this 21st day of June, 1919.

WINDSOR COBB.
